UNITED STATES PATENT OFFICE.

ROBERT LOUIS NEUBERT, OF SUPERIOR, WISCONSIN.

DOOR LATCH AND HOLDER.

Application filed October 9, 1926. Serial No. 140,560.

- This invention provides latching and holding means for swinging closures, such as doors, gates and barriers, to secure the door or like parts both when open or closed.
- 5 The invention supplies means designed chiefly for garage and barn doors to prevent opening thereof from the outside and to hold the same when swung open to the required position.
- 10 The invention further aims to provide means of the general nature stated which may be applied to any swinging door and serve as latching means therefor, or as holding means to secure the door when open and 15 prevent movement thereof by a draft of air or other cause tending to prematurely close the door when it is required to maintain it in open position.
- 15 While the drawings illustrate a preferred embodiment of the invention, it is to be understood that in adapting the means to meet specific needs and requirements, the design may be varied and such other changes in the minor details of construction may be 20 resorted to within the scope of the invention as claimed, without departing from the spirit thereof.
- 25 For a full understanding of the invention and the merits thereof reference is to be had to the following description and the drawings hereto attached, in which,—
- 30 Figure 1 is an elevational view of the invention showing the same applied to a pair of swinging doors.
- 35 Figure 2 is a horizontal sectional view on the line 2—2 of Figure 1, and
- 40 Figure 3 is a fragmentary view showing the relation of the parts when the fastener is in position to hold a door in the required open position.
- 45 Corresponding and like parts are referred to in the following description and designated in the several views of the drawings by like reference characters.
- 50 The numerals 1 and 2 designate a pair of doors which are hinged to swing outwardly from a closed position. The numeral 3 designates an enclosing wall of a garage, barn, or like structure, in which is formed the opening to which the doors 1 and 2 are fitted. The numeral 4 designates jambs at opposite sides of the door opening. A bar 5 is secured at its ends to each of the doors 1 and 2 and its intermediate portion is spaced from the respective walls, as indicated most clearly in Figure 2. A plurality of notches 6 are formed in the upper edge of each of the bars 5 and are adapted to co-operate with a loop 7 at the swinging end of a pivoted latch member 8. A bracket 9 is secured to each of the jambs 4 and the respective members 8 are pivoted thereto in a manner to admit of the outer end having a limited vertical movement and a sliding movement along the intermediate portion of the respective bars 5. When the doors are closed the upper closed ends of the loops 7 engage the outermost notches 6, thereby serving to secure the doors. When the doors are swung into open position, the loops 7 engage the innermost notches 6 and prevent movement of the doors in either position, thereby guarding against premature closing of the doors when driving therethrough. The latch member 8 may be utilized as means for swinging the door open or closed, after its free end has been lifted a distance to disengage it from the notches 6. When the swinging end of the members 8 has been elevated to clear the notches 6 said member may be swung outwardly to open the door, or drawn inwardly to close the door, and when the member is released it drops and seats the loop 7 in the desired notch 6, thereby holding the door either open, or closed, as required.
- 55 In the case of double doors, a latch 10 is pivoted to the outer end of one of the bars 5 and is adapted to engage the outer end of the companion bar 5 to assist materially in holding the doors in closed position, said latch overlapping the joint formed between the meeting ends of the doors, as indicated most clearly in Figures 1 and 2 of the drawings.
- 60 Having thus described the invention, I claim:
- 65 The combination with a pair of swinging doors, a bar attached to a side of each of the doors and having a portion spaced there-
- 70
- 75
- 80
- 85
- 90
- 95
- 100

from and provided in its length with notches, a member pivoted at its inner end to the part to which the respective doors are hinged and having its outer portion slidingly engaging the spaced portion of the adjacent one of said respective bars and adapted to enter a notch thereof, and a latch pivoted

to the outer end of one of the bars and adapted to overlap and engage the adjacent end of the other bar to assist materially in holding the doors closed.

In testimony whereof I affix my signature.

ROBERT LOUIS NEUBERT. [L.S.]
